HOUSING FOR A PORTABLE PHONOGRAPH OR SIMILAR ARTICLE

Hugo Hendrik Maria Vananderoye, Hasselt, Belgium, assignor, by mesne assignments, to U.S. Philips Corporation, New York, N.Y., a corporation of Delaware

Filed Oct. 16, 1968, Ser. No. 14,007

Claims priority, application Switzerland Apr. 22, 1968

Term of patent 14 years

Int. Cl. D14—01

U.S. Cl. D56—4

FIG. 1 is a perspective view of the housing for a portable phonograph or similar article, showing my new design;

FIG. 2 is a top plan view;

FIG. 3 is a bottom plan view;

FIG. 4 is a side elevational view;

FIG. 5 is an elevational view of the opposite side;

FIG. 6 is a front elevational view;

FIG. 7 is a rear elevational view.

I claim:

The ornamental design for a housing for a portable phonograph or similar article, as shown.
